ABSTRACT OF THE DISCLOSURE

A cage composed of a yoke and basket is rigidly and coaxially carried on the lower end of a reach rod mounted to be lowered into a tiltable steel-making vessel. A crucible is removably positioned in the basket and, when the latter is immersed in the vessel contents, collects a sample therefrom. Cooperating means on the yoke and crucible limit flotation uplift of the latter in the former. On partial rotation of the crucible in the basket, disengagement of such means permits removal and replacement of the crucible. The reach rod is suspended from a jib crane for convenient manipulation.

BACKGROUND OF THE INVENTION

This invention relates to apparatus for taking samples from a tiltable steel-making vessel. More particularly, it concerns a sampling cup or crucible removably carried in a cage fixed to a reach rod for lowering into the vessel.

The most pertinent prior art known to us is the Long et al. Patent No. 2,598,183.

SUMMARY OF THE INVENTION

In a preferred embodiment, we attach a cage to the lower end of a reach rod arranged to be lowered into the top of a steel-making vessel, and provide a crucible removably disposed in the cage for holding a sample. The rod is guided by a sleeve on a jib crane which suspends the rod. The cage is adapted to enter a port in the inclined fume-exhaust duct extending upwardly from the vessel, before it enters the latter.

BRIEF DESCRIPTION OF THE DRAWINGS

A complete understanding of our invention may be obtained from the following detailed description which refers to the accompanying drawings illustrating a present preferred embodiment.

In the drawings:

FIGURE 1 is a diagrammatic elevation of an installation of our invention on a conventional steel-making vessel;

FIGURE 2 is a plan view of our cage and crucible, showing the suspended reach rod in section;

FIGURE 3 is an elevation of our cage and crucible, showing the guide sleeve in vertical section; and

FIGURE 4 is an elevation taken at right angles to that from which FIGURE 3 is taken.

DETAILED DESCRIPTION OF THE PREFERRED EMBODIMENT

Referring now in detail to the drawings and, for the present, to FIGURE 1 particularly, a conventional steel-making vessel 10 is tiltably mounted in suitable supports (not shown) and has an open top. An inclined fume-exhaust duct 11 is positioned to register with the top of the vessel when it is erect. A port 12 is formed in the duct.

2

On a floor or deck 13 above vessel 10, a jib crane 14 is mounted for angular movement from a position over duct 11 to a position laterally thereof. Crane 14 has a guide sleeve 15 fixed thereto through which a reach rod 16 reciprocates, as controlled by the hoist rope of the crane. Sample collecting means 17 is mounted on the lower end of rod 16.

Turning now to FIGURES 2-4, sampling means 17 includes an elongated cage 18 and a cup or crucible 19 removably positioned therein. Cage 18 is of heavy heat-resistant metal construction, either cast or fabricated, and has a lower basket portion 20 from which a yoke 21 extends upwardly. The yoke is welded or otherwise secured to rod 16. Basket portion 20 preferably comprises a ring 22 and four circumferentially spaced arms 23 which extend downwardly and inwardly therefrom, uniting at a central point. Crucible 19 of suitable refractory material is received and loosely confined in basket portion 20.

Yoke 21 extends upwardly from ring 22 a distance sufficient to accommodate the height of crucible 19 when the latter is moved from a lateral position into axial alignment with cage 18. Each limb of yoke 21 has an inwardly extending abutment 24. Crucible 19 has diametrically opposed laterally projecting ears 25. When the crucible is positioned so that a line through the ears is normal to the plane of yoke 21, the crucible may be lowered to rest in basket 20, the ears passing between the abutments. If the crucible be then rotated one quarter of a turn, ears 25 will engage abutments 24 when uplifted by flotation, on immersion of the cage in the contents of vessel 10. Reversing this procedure on lifting the cage from the vessel permits easy removal of the crucible and sample.

The several advantages of my invention should be readily apparent. The structure is simple yet sturdy and well adapted to the extreme service conditions for which it is intended and its operation requires no skill nor does it necessitate stopping the steel-making process. It is rapid in operation, furthermore, which is very important in making steel by modern methods, such as oxygen blowing, where the composition of the heat varies at a high rate, particularly toward the end of the blow.

What is claimed is:

1. Apparatus for sampling molten metal comprising a reach rod, an elongated cage rigidly mounted on the end of said rod coaxially therewith, a crucible removably disposed in said cage, laterally extending ears on said crucible, and spaced abutments on said cage engageable by said ears to limit flotation uplift of the crucible on immersion of the basket.

2. An apparatus as defined in claim 1, characterized by said ears and abutments being spaced about the common axis of said crucible and cage, respectively, so that in one position of the crucible in the cage, said ears clear said abutments, on relative axial movement of the cage and crucible for insertion and removal of the latter into and from the former.
